RADIO REPEATER

J. Ernest Smith, Brooklyn, N. Y., assignor to Radio Corporation of America, a corporation of Delaware

Application February 12, 1942, Serial No. 430,527

30 Claims. (Cl. 250—15)

1

The present invention relates to radio repeater or relay stations and, more particularly, to such stations as are adapted to utilize ultra-high frequency waves for relaying television or similar signals.

In ordinary transmission parlance, a repeater is considered to be an amplifier having an output signal frequency dependent upon the frequency of the input signal. Amplification of frequencies in the neighborhood of 500 megacycles for a band width sufficient for high fidelity television transmission is difficult with many amplifier tubes available at the present time. To overcome this difficulty, the ultra high frequency signal is heterodyned to a lower frequency band, amplified and heterodyned back to an ultra high frequency band for retransmission. Further, the retransmitted band normally does not coincide with the received frequency band but is differentially spaced therefrom to avoid feedback between the transmitting and receiving antennas and their associated circuits. While the present heterodyning practice permits satisfactory amplification at ultra high frequencies, it introduces, at the same time, the necessity for frequency monitoring of the retransmitted signal since its frequency is a function of the heterodyning oscillator frequency. Moreover, if the relay system incorporates antennas having band widths sufficient for the simultaneous transmission of a video channel and an adjacent sound or "cue" channel, it is possible for cross-talk to result due to drift of the heterodyning frequencies at one of the repeaters.

An object of the present invention is to overcome the foregoing difficulties and disadvantages.

A further object of the present invention is to improve the frequency stability of radio relay equipment.

Another object of the present invention is the provision of a radio relay station which may be conveniently controlled and supervised from the terminal stations of a relay system.

A further object of the present invention is the provision of a relay system which will not require frequency monitoring at each of the intermediate repeater stations.

Still a further object of the present invention is the provision of a system of amplifying ultra-high frequency radio waves wherein the output signal from the amplifier means is determined substantially only by the frequency of the incoming waves.

The foregoing objects and others, which may appear from the following detailed description,

2

are obtained in accordance with the principles of the present invention by providing a crystal controlled oscillator and another oscillator, mixing the output of said oscillators or modulating the output of one of the oscillators, either in amplitude or wavelength, by the other of the oscillators and separating the sum and difference frequencies thus obtained. One of these frequencies is mixed with an incoming band of frequencies to obtain a signal at a comparatively low intermediate frequency which may be conveniently amplified without adversely affecting the width of the band of the frequencies. The amplified band of frequencies is then mixed with the other of the sum and difference frequencies to convert the band to a position in the radio frequency spectrum near that of the incoming band of frequencies and, also, thus dropping out the effect of any frequency drift in the local oscillator. The converted band of frequencies is then transmitted to the succeeding amplifiers in the relay system.

The present invention will be more fully understood by reference to the following detailed description which is accompanied by a drawing in which:

Figure 1 illustrates the frequency distribution, in a portion of the radio frequency spectrum, of various frequencies used in an embodiment of the invention; while

Figure 2 is a diagram in conventional block formation of an embodiment of the invention;

Figure 3 is a curve illustrating the operation of a portion of Figure 2; and

Figure 4 illustrates a modification of the embodiment of Figure 2, and a different order of application of the operations of the invention.

Reference will now be had to the drawing. Figure 1 shows the frequency spectrum arrangement 40 wherein the incoming frequency f_s is heterodyned with a local frequency $(f_c - f_k)$ giving the low intermediate frequency band $(f_s - f_c + f_k)$ which may be amplified without difficulty. The amplified signal is then heterodyned with another local frequency $(f_c + f_k)$, thus resulting in the frequency $(f_s + 2f_k)$ which is to be retransmitted. The frequencies f_c and f_k from which the sum and difference frequencies are derived are locally produced by oscillation generators, that for frequency f_k being crystal controlled. It will be noted that the outgoing frequency $(f_s + 2f_k)$ is independent of the oscillator frequency f_c .

The frequency f_k may conveniently be of the order of 10 megacycles and is, therefore, preferably derived from a crystal oscillator. Its drift,

therefore, compared to the outgoing carrier frequency of the order of 500 megacycles is negligible.

In Figure 2 is shown an embodiment of the invention for performing the operations outlined above. Frequency f_k is generated by crystal oscillator 10 and applied to balanced modulator 12 in a push-pull relationship. Another frequency f_c generated by oscillator 14 is applied to balanced modulator 12 in push-push relationship. This is a well known carrier suppression system of modulation and therefore needs no further description.

The output frequencies from balanced modulator 12 consist substantially of two side bands only, namely, $(f_c - f_k)$ and $(f_c + f_k)$. The frequency $(f_c - f_k)$ is applied to converter 16 and there heterodyned with an incoming signal f_s arriving from a preceding station by way of receiving antenna RA, giving an intermediate frequency $(f_s - f_c + f_k)$. This frequency may be amplified in a conventional amplifier 18 to any desired extent. After amplification the intermediate frequency signal is heterodyned with the component $(f_c + f_k)$ in converter 20 thus producing the output frequency $(f_s + 2f_k)$. The output frequency is applied to transmitting antenna TA for retransmission to succeeding relay stations. The antennas RA and TA are preferably of the directive type with their zones of maximum response directed away from each other and toward relay stations.

It should be understood that the frequency components shown in Figures 1 and 2 and specifically mentioned are those which are essential to the operation of the system. Other modulation products would be present but selective circuits in the system may be provided to discriminate against them. Therefore, in order to reduce the number of other modulation products a filter 30 is provided in the channel between converter 20 and modulator 12 and a filter 32 is provided between converter 16 and modulator 12. These filters assure that only a single frequency as indicated is fed to each converter. Then the output of converter 16 may be arranged to pass only the desired difference frequency $f_s - f_c + f_k$ while discriminating, for example, against the sum frequency $f_s + f_c - f_k$. Likewise, the output of converter 20 may be arranged to pass only the sum frequency $f_s + 2f_k$ discriminating, for example, against the difference frequency $f_s - 2f_c$. In order to illustrate the stability of the outgoing signal $(f_s + 2f_k)$, suppose a frequency drift of 5 kilocycles is allowed crystal oscillator 10. The outgoing signal then has a maximum drift of 10 kilocycles in 50 megacycles or .002 percent which, for all practical purposes, is negligible. Obviously, the method described above is equally applicable to an amplitude or to a frequency modulation system.

The system as so far described insures that the retransmitted frequency band will not drift. It does not, however, maintain the frequency band to be amplified, that is, the frequency $(f_s - f_c + f_k)$, constant since this frequency is a function of f_c . Due to the difficulty of obtaining wide enough pass bands at low frequencies to obviate the effect of this drift, according to a further aspect of the present invention, automatic frequency control of oscillator 14 may be provided. Side band clipping in amplifier 18 is thus prevented since the position of band $(f_s - f_c + f_k)$ is maintained constant. This may be accomplished by supplying discriminator unit 22, responsive to the

frequencies in the output of modulator 12. Discriminator 22 may be a conventional frequency modulation receiver incorporating a back-to-back discriminator and an amplitude detector. The discriminator 22 should have a characteristic with respect to the frequencies $(f_c - f_k)$ and $(f_c + f_k)$ as shown in Figure 3, wherein curves 24 and 26 illustrate the frequency-output voltage characteristics of the halves of the back-to-back discriminator. It will be seen that as long as the frequency $(f_c - f_k)$ and the frequency $(f_c + f_k)$ cut curves 24 and 26 at points equally distant from the cross over point the output potential is zero. A shift in either direction will result in a positive or negative resultant output potential. This direct resultant output potential is arranged to be applied as a variable bias to oscillator 14 whereby the frequency f_c is controlled in such sense that the output frequencies of modulator 12 are shifted in the desired direction.

In Figure 4 is shown a modification of the embodiment of Figure 2 wherein the balanced modulator arrangement 12 of Figure 2 is not used. In this figure the incoming frequency is shown as $(f_s + 2f_k)$, the output frequency of the embodiment of Figure 2. The discriminatory characteristics of filter networks 30 and 32 are relied upon to select the first lower and upper side bands $(f_c - f_k)$ and $(f_c + f_k)$ resulting from a mixing of frequencies f_c and f_k , in modulator 24, while rejecting the frequency f_c and components of higher order. Since rather severe selectivity is required of filter networks 30 and 32 to discriminate against the frequency f_c while passing frequencies $(f_c - f_k)$ and $(f_c + f_k)$ for straight mixing or amplitude modulation, the crystal oscillator output f_k may be arranged to frequency modulate in modulator 24 the frequency f_c generated by oscillator 14. The modulation index may be adjusted to emphasize the first of the side bands with respect to the frequency f_c and higher order components. For example, if a modulation index of about 2.4 is used, the amplitude of frequency f_c is reduced to zero and at the same time the maximum fundamental or first order side band amplitudes are obtained. The channel carrying frequencies $(f_c + f_k)$ and $(f_c - f_k)$ may include an amplitude limiting transducer device if desired. While I have used a modulation index of 2.4 in order to illustrate the selective property of this type of modulation, it is to be clearly understood that my invention is not limited to that value, since under some circumstances a modulation index of about 1.8 may be preferable. A modulation index of this order gives a maximum ratio of fundamental to carrier and fundamental to second order side band amplitudes. The amplified intermediate frequency is $f_s - f_c + f_k$, the same as in the previous example. It is then heterodyned with the other side band frequency $(f_c - f_k)$ and the upper beat frequency, which becomes f_s , selected for retransmission. The outgoing frequencies of the repeaters using alternate orders of application of the side band frequencies thus are alternately f_s and $(f_s + 2f_k)$ throughout the system.

While I have particularly described and illustrated several modifications of the present invention, it should be distinctly understood that my invention is not limited thereto but may be varied within the scope of the appended claims.

I claim:

1. In a radio relay system, a station including receiving and transmitting antennae, a low frequency oscillator of high frequency stability, an

other oscillator, modulator means for so combining the output of said oscillators that sum and difference frequencies are generated, a first converter means for mixing one of said frequencies with incoming high frequency energy from said receiving antenna for obtaining a low intermediate frequency, means for amplifying said intermediate frequency, a second converter means for mixing the other of said sum and difference frequencies with said amplified intermediate frequency to obtain output energy at a high frequency adjacent the frequency of said incoming energy and means for applying said output energy to said transmitting antenna for radiation.

2. In a radio system, a source of high frequency energy, a low frequency oscillator of high frequency stability, another oscillator, modulator means for so combining the output of said oscillators that sum and difference frequencies are generated, a first converter means for mixing one of said sum and difference frequencies with said first mentioned high frequency energy for obtaining a low intermediate frequency, means for amplifying said intermediate frequency, a second converter means for mixing the other of said sum and difference frequencies with said amplified intermediate frequency to obtain output energy at a high frequency adjacent the frequency of said source.

3. In a radio relay system, a station including receiving and transmitting antennae, a low frequency oscillator of high frequency stability, another oscillator, modulator means for so combining the output of said oscillators that sum and difference frequencies are generated, a first converter means for mixing said difference frequency with incoming high frequency energy from said receiving antenna for obtaining a low intermediate frequency, means for amplifying said intermediate frequency, a second converter means for mixing said sum frequency with said amplified intermediate frequency to obtain output energy at a high frequency adjacent the frequency of said incoming energy and means for applying said output energy to said transmitting antenna for radiation.

4. In a radio system, input and output circuits for high frequency energy, a low frequency oscillator of high frequency stability, another oscillator, modulator means for so combining the output of said oscillators that sum and difference frequencies are generated, a first converter means for mixing said difference frequencies with high frequency energy from said input circuit for obtaining a low intermediate frequency, means for amplifying said intermediate frequency, a second converter means for mixing said sum frequency with said amplified intermediate frequency to obtain output energy at a high frequency adjacent the frequency of the energy at said input circuit and means for applying said output energy to said output circuit.

5. In a radio relay system, a station including receiving and transmitting antennae, a low frequency oscillator of high frequency stability, another oscillator, modulator means for so combining the output of said oscillators that side band frequencies are generated, a first converter means for mixing one of said side band frequencies with incoming high frequency energy from said receiving antenna for obtaining a low intermediate frequency, means for amplifying said intermediate frequency, a second converter means for mixing the other of said side band frequencies with said amplified intermediate frequency to obtain output energy at a high frequency adjacent the frequency of the energy at said input circuit and means for applying said output energy to said output circuit.

put energy at a high frequency adjacent the frequency of said incoming energy and means for applying said output energy to said transmitting antenna for radiation.

6. In a radio system, a station including receiving and transmitting antennas, a low frequency oscillator of high frequency stability, another oscillator, means for so applying the output of said low frequency oscillator to said other oscillator that the wavelength of the output is modulated thereby, a first converter means for mixing one output frequency with incoming high frequency energy from said receiving antenna for obtaining a low intermediate frequency, means for amplifying said intermediate frequency, a second converter means for mixing another of said output frequencies with said amplified intermediate frequency to obtain output energy at a high frequency adjacent the frequency of said incoming energy and means for applying said output energy to said transmitting antenna for radiation.

7. In a radio relay system, a station including receiving and transmitting antennae, a low frequency oscillator of high frequency stability, another oscillator, modulator means for so combining the output of said oscillators that sum and difference frequencies are generated, a first converter means for mixing one of said frequencies with incoming high frequency energy from said receiving antenna for obtaining a low intermediate frequency, means for amplifying said intermediate frequency, a second converter means for mixing the other of said sum and difference frequencies with said amplified intermediate frequency to obtain output energy at a high frequency adjacent the frequency of said incoming energy and means for applying said output energy to said transmitting antenna for radiation, means equally responsive in opposite senses to said sum and difference frequencies for obtaining a control potential and means for applying said potential to control the frequency of said other oscillator.

8. In a radio relay system, a station including receiving and transmitting antennae, a low frequency oscillator of high frequency stability, another oscillator, means for so modulating the frequency of said other oscillator by said low frequency oscillator that sum and difference frequencies are generated, a first converter means for mixing one of said frequencies with incoming high frequency energy from said receiving antenna for obtaining a low intermediate frequency, means for amplifying said intermediate frequency, a second converter means for mixing the other of said sum and difference frequencies with said amplified intermediate frequency to obtain output energy at a high frequency adjacent the frequency of said incoming energy and means for applying said output energy to said transmitting antenna for radiation.

9. In a radio relay system, a station including receiving and transmitting antennae, a low frequency oscillator of high frequency stability, another oscillator, means for so modulating the frequency of said other oscillator by said low frequency oscillator that sum and difference frequencies are generated, a first converter means for mixing one of said frequencies with incoming high frequency energy from said receiving antenna for obtaining a low intermediate frequency, means for amplifying said intermediate frequency, a second converter means for mixing the other of said sum and difference frequencies with said amplified intermediate frequency to obtain output energy at a high frequency adjacent the frequency of the energy at said input circuit and means for applying said output energy to said output circuit.

frequency of said incoming energy and means for applying said output energy to said transmitting antenna for radiation, means equally responsive in opposite senses to said sum and difference frequencies for obtaining a control potential and means for applying said potential to control the frequency of said other oscillator.

10. In a radio relay system, a station including receiving and transmitting antennae, a low frequency oscillator of high frequency stability, another oscillator, modulator means for so combining the output of said oscillators that sum and difference frequencies are generated, a first converter means for mixing said difference frequency with incoming high frequency energy from said receiving antenna for obtaining a low intermediate frequency, means for amplifying said intermediate frequency, a second converter means for mixing said sum frequency with said amplified intermediate frequency to obtain output energy at a high frequency adjacent the frequency of said incoming energy and means for applying said output energy to said transmitting antenna for radiation, means equally responsive in opposite senses to said sum and difference frequencies for obtaining a control potential and means for applying said potential to control the frequency of said other oscillator.

11. In a radio relay system, a station including receiving and transmitting antennas, a low frequency oscillator of high frequency stability, another oscillator, means for frequency modulating said other oscillator by said low frequency oscillator, the modulation index being such that the sum and difference frequencies predominate in the output, a first converter means for mixing said difference frequency with incoming high frequency energy from said receiving antenna for obtaining a low intermediate frequency, means for amplifying said intermediate frequency, a second converter means for mixing said sum frequency with said amplified intermediate frequency to obtain output energy at a high frequency adjacent the frequency of said incoming energy and means for applying said output energy to said transmitting antenna for radiation.

12. In a radio relay system, a station including receiving and transmitting antennas, a low frequency oscillator of high frequency stability, another oscillator, means for frequency modulating said other oscillator by said low frequency oscillator, the modulation index being such that the sum and difference frequencies predominate in the output, a first converter means for mixing said difference frequency with incoming high frequency energy from said receiving antenna for obtaining a low intermediate frequency, means for amplifying said intermediate frequency, a second converter means for mixing said sum frequency with said amplified intermediate frequency to obtain output energy at a high frequency adjacent the frequency of said incoming energy and means for applying said output energy to said transmitting antenna for radiation, means equally responsive in opposite senses to said sum and difference frequencies for obtaining a control potential and means for applying said potential to control the frequency of said other oscillator.

13. In a radio relay system, a station including receiving and transmitting antennas, a low frequency oscillator of high frequency stability, another oscillator, modulator means for so combining the output of said oscillators that sum and difference frequencies are generated, a first converter means for mixing said sum frequency with

5 incoming high frequency energy from said receiving antenna for obtaining a low intermediate frequency, means for amplifying said intermediate frequency, a second converter means for mixing said difference frequency with said amplified intermediate frequency to obtain output energy at a high frequency adjacent the frequency of said incoming energy and means for applying said output energy to said transmitting antenna for radiation, means equally responsive in opposite senses to said sum and difference frequencies for obtaining a control potential and means for applying said potential to control the frequency of said other oscillator.

10 14. In a radio relay system, a station including receiving and transmitting antennas, a low frequency oscillator of high frequency stability, another oscillator, means for modulating the wavelength of the output of said other oscillator by said low frequency oscillator, a first converter means for mixing the first upper sideband frequencies of the output of said modulator means with incoming high frequency energy from said receiving antenna for obtaining a low intermediate frequency, means for amplifying said intermediate frequency, a second converter means for mixing the first lower sideband frequency of the output of said modulator means with said amplified intermediate frequency to obtain output energy at a high frequency adjacent the frequency of said incoming energy and means for applying said output energy to said transmitting antenna for radiation.

15 15. In a radio relay system, a station including receiving and transmitting antennas, a low frequency oscillator of high frequency stability, another oscillator, means for modulating the wavelength of the output of said other oscillator by said low frequency oscillator, filter means for separating the sum frequency and the difference frequency from the output of said modulator, a first converter means for mixing one of said frequencies with incoming high frequency energy from said receiving antenna for obtaining a low intermediate frequency, means for amplifying said intermediate frequency, a second converter means for mixing the other of said sum and difference frequencies with said amplified intermediate frequency to obtain output energy at a high frequency adjacent the frequency of said incoming energy and means for applying said output energy to said transmitting antenna for radiation.

16. A radio relay system including a plurality of stations as set forth in claim 1, alternate ones of said stations utilizing said difference frequency in said first converter and said sum frequency in said second converter, the other stations of said system having the order of application of said sum and difference frequencies reversed.

17. A radio relay system including a plurality of stations as set forth in claim 8, alternate ones of said stations utilizing said difference frequency in said first converter and said sum frequency in said second converter, the other stations of said system having the order of application of said sum and difference frequencies reversed.

18. A radio relay system including a plurality of stations as set forth in claim 9, alternate ones of said stations utilizing said difference frequency in said first converter and said sum frequency in said second converter, the other stations of said system having the order of application of said sum and difference frequencies reversed.

19. In a radio system, a source of high frequency energy, a low frequency oscillator of high

frequency stability, another oscillator, modulator means for so combining the output of said oscillators that sum and difference frequencies are generated, a converter means for mixing one of said sum and difference frequencies with said first mentioned high frequency energy for obtaining a low intermediate frequency and means for obtaining a control potential from said low intermediate frequency and means for utilizing said control potential to control the frequency of said other oscillator.

20. In a radio system, a low frequency oscillator of high frequency stability, another oscillator, means for so applying the output of said low frequency oscillator to said other oscillator that the wavelength of the output is modulated thereby, converter means for mixing one output frequency from said modulating means with other high frequency energy to obtain a low intermediate frequency and utilization means for said low intermediate frequency.

21. In a radio system, a station including a receiving antenna, a low frequency oscillator of high frequency stability, another oscillator, means for so modulating the frequency of said other oscillator of said low frequency oscillator that sum and difference frequencies are generated, converter means for mixing one of said frequencies with incoming high frequency energy from said receiving antenna for obtaining a low intermediate frequency, utilization means for said intermediate frequency and means equally responsive in opposite senses to said sum and difference frequencies for obtaining a control potential and means for applying said potential to control the frequency of said other oscillator.

22. In a radio system, a station including a receiving antenna, a low frequency oscillator of high frequency stability, another oscillator, means for modulating the wavelength of the output of said other oscillator by said low frequency oscillator, converter means for mixing the first upper sideband frequencies of the output of said modulator means with incoming high frequency energy from said receiving antenna for obtaining a low intermediate frequency, and means for amplifying said intermediate frequency.

23. The method of wave conversion which includes generating a relatively low frequency local wave, generating a local carrier wave, frequency modulating the carrier wave with the local wave to such a degree that the carrier has substantially zero value in the waves resulting from the modulation process in order to facilitate filtering of side bands on either side of the carrier, filtering a side band frequency resulting from the modulation process, heterodyning a wave to be converted with the filtered side band, and utilizing a beat wave resulting from the heterodyning process.

24. The method of wave conversion which includes generating a relatively low frequency local wave, generating another local wave, frequency modulating said other local wave with the first mentioned local wave to such a degree that the said other local wave has substantially zero value in the waves resulting from the modulation process in order to facilitate selection of one of the remaining modulation products, selecting a side band frequency resulting from the modulation process, heterodyning a wave to be converted with the selected side band, and utilizing a beat wave resulting from the heterodyning process.

25. The method of wave conversion which in-

cludes generating a relatively low frequency local wave, generating a local carrier wave, frequency modulating the carrier wave with the local wave to such a degree that the carrier has substantially zero value in the waves resulting from the modulation process in order to facilitate filtering of side bands on either side of the carrier, filtering a side band frequency resulting from the modulation process, heterodyning the wave to be converted with the filtered side band, selecting a beat wave resulting from the heterodyning process, heterodyning the beat to a high frequency, and utilizing the resultant high frequency wave.

26. The method of wave conversion which includes generating a local wave, generating a local carrier wave, frequency modulating the carrier with the local wave to such a degree that the carrier is reduced substantially to zero in the waves resulting from the modulation process in order to facilitate filtering of side bands apart from the carrier, filtering a side band frequency wave lying to one side of the carrier frequency, heterodyning a wave to be converted with the filtered side band frequency wave, amplifying a beat wave resulting from the heterodyning process, and heterodyning the amplified beat with another side band frequency filtered from the modulated waves.

27. The method of converting modulated waves of a given mean frequency to modulated waves of another mean frequency which includes generating a local relatively high frequency carrier wave, generating a relatively low frequency wave, producing sum and difference frequencies with the locally generated waves, successively heterodyning waves derived from the modulated waves of given mean frequency with the said sum and difference waves, and utilizing a beat wave derived from the last heterodyning process.

28. The method of converting modulated waves of given mean frequency to waves of another mean frequency which includes generating a local carrier wave, generating a local constant frequency modulating wave, carrier suppression modulating the carrier with the low frequency modulating wave, filtering the side bands resulting from the modulation, heterodyning the modulated waves of mean frequency with one of the side bands to produce a relatively low, readily amplifiable modulated intermediate frequency wave, amplifying the relatively low, readily amplifiable intermediate frequency wave, and heterodyning the amplified intermediate frequency wave against the other filtered side band to produce the modulated waves of the desired mean frequency.

29. The method as defined in the claim 28 which includes the step of utilizing a portion of the carrier suppression modulated waves to control the frequency of one of the locally generated waves.

30. The method of wave conversion which includes locally generating a pair of waves of different frequency, producing sum and difference frequency waves from the locally generated waves, utilizing a portion of the sum and difference waves to frequency control the frequency of one of the locally generated waves, and successively heterodyning waves derived from waves of one mean frequency with said sum and difference frequency waves to produce a wave of different mean frequency.

J. ERNEST SMITH.
